WATER CLOSET

William H. Armstrong, Birmingham, Mich., assignor to
Borg-Warner Corp., a corporation of Illinois

Filed Dec. 30, 1963, Ser. No. 77,966

Term of patent 14 years

(Cl. D4—5)

FIG. 1 is an isometric view of a water closet, showing my new design;

FIG. 2 is a front elevation thereof; and

FIG. 3 is a side elevation thereof.

I claim:

The ornamental design for a water closet, substantially as shown.
